MACHINE OR APPARATUS FOR SHAPING
METAL TUBES, CONTAINERS, AND THE
LIKEJohn Arthur Dove, Sutton-in-Ashfield, England,
assignor to Barringer, Wallis & Manners, Limited,
Rock Valley, Mansfield, EnglandApplication April 21, 1939, Serial No. 269,275
In Great Britain April 25, 1938

3 Claims. (Cl. 113—52)

This invention comprises improvements in machines or apparatus for shaping metal tubes, containers and the like, and is primarily concerned with the shaping of thin sheet metal articles by the exercise of pressure thereon at the part or parts to be shaped.

The invention refers more particularly to that kind of machine wherein the shaping of tubular, cylindrical or annular bodies, such for example as sheet metal containers, is effected by a bulging or expanding tool operating within the work while the latter is suitably supported.

An important object of the present invention is to provide simple and effective means for supporting the work in the machine during the shaping operation, and for enabling said work to be easily and rapidly assembled in and removed from said supported position.

According to the present invention, in a machine or apparatus of the kind aforesaid there is provided an outer or female die which accommodates the work during the shaping operation and is so constructed that said work can be assembled within and removed from the die in a lateral direction, i. e., in a direction at right angles to the axial or longitudinal centre of the work.

More particularly the outer or female die for accommodating the work while being shaped comprises a plurality of hinged sections capable of being opened for insertion of the work therein and closed upon the work during the shaping operation; means being also included for releasably fastening the hinged die in the closed position.

The invention also includes means whereby during the shaping of the work at least one end of the work has exerted thereon a yielding or resilient pressure.

For the purpose of more fully describing the nature of this invention, reference will now be made to the accompanying drawings, wherein:

Figure 1 illustrates in part sectional elevation a hinged outer or female die according to this invention in the open position, together with an axially displaceable end support for the work.

Figure 2 is a vertical section on 2—2 of Figure 1.

Figure 3 illustrates in part sectional elevation the die in the closed position, the axially displaceable end support moved to a position engaging the end of the work, and a shaping tool in its operative position within the work.

Figure 4 is an enlarged sectional elevation through the hinged die and illustrating a box 55

therein after being shaped, the box having one end closed and having a side seam which is locked at the end remote from said closed end.

Figure 5 is an enlarged perspective view illustrating one method of locking the end of the side seam of a box to be shaped.

Figure 6 is a section on 6—6 of Figure 5.

Figure 7 is a section on 7—7 of Figure 5.

Figure 8 illustrates in part sectional elevation a modified construction of outer die with shaped box therein, and also including a spring pressed end support for the work.

By way of example the invention will be described as applied to a machine such as that set forth in the specification of my prior co-pending application filed August 30, 1937, Serial No. 161,707 now Patent No. 2,194,385, dated March 19, 1940. This machine is for shaping tubular or similar articles either seamed or seamless and having either one end or both ends open, the shaping being effected by the application of pressure on the interior of the work; there being provided a relatively reciprocatable headstock and tool holder and means for supporting the work on the headstock so as to present an open end of the work to the expanding tool for permitting entry and removal of said tool. The tool advantageously comprises a plurality of pressure members movable outwards to exert pressure on the work-piece for expanding or bulging same to the required shape, and means are also provided for effecting relative rotation and/or reciprocation between the work and the tool during the shaping operation. Also the headstock has associated therewith end supports for the work between which said work is releasably clamped or gripped during the shaping operation.

In the application of the present invention to a machine as above, an outer or female die 10 is suitably fitted between the two end supports for the work, said die having its inner face shaped to the required contour of the wall of the finished article. This die is advantageously of cylindrical or sleeve-like formation and is divided diametrically into two halves 11, 12, one half 11 being suitably fixed while the other half 12 is hinged to said fixed half so as to be capable of being swung open for permitting assembly in the die of the work 13 to be shaped and removal of the shaped article. A handle 14 may be provided on the hinged half of the die for facilitating opening and closing thereof, and means are provided for fastening the two halves in the closed position.

Where the work is assembled and gripped be-

tween two end supports 15, 16, at least one of said end supports is arranged to be axially displaced for facilitating assembly and removal of the work in the machine. For example, one end support 16 associated with the headstock may form part of or be carried by a sleeve 17 that is rotatably mounted upon a non-rotatable boss or the like 18, there being a pin and inclined or cam slot connection 19, 20 between the boss and sleeve and a handle 21 upon the latter, so that by rotating the sleeve on the boss the end support 16 may be caused to approach or recede from the opposite end support 15.

In some cases the outer die 10 may be formed with at least one part of its length spring-loaded. In other words, the die may be divided in a direction at right angles to its axis, and springs or like resilient elements incorporated at the division or divisions so as to permit of a limited degree of axial extension and contraction of the die. For example, one end portion 22 of the die (Figure 8) may be so spring-loaded, by a plurality of spaced compression springs 23 in opposed pockets 24; and with such an arrangement, when the die is closed on to the work and an axially displaceable end support 16 (such as that before-described) is moved up to the work, the spring-loaded portion 22 of the die is axially moved a short distance to compress the springs 23 and contract said die. When the end support 16 is moved away from the work after the shaping operation, the spring elements 23 of the spring-loaded portion 22 of the die 10 function to displace said portion axially and slightly extend the die. The end 22 is guided and limited in its axial movement and prevented from rotation by pins 25 co-operating with holes 26. The spring-loading of the part 22 serves to assist in releasing the grip of the outer die on the work and consequently also assist in the easy and rapid removal of the shaped article when the die is opened. More particularly is this the case where the article being bulged is of polygonal shape or formed with flats and/or where bulging is effected along a portion of the length of the article or along a portion of the article spaced from each end thereof. The die is advantageously secured in the closed position during the shaping operation by a short arm or angle plate 27 fixed to the axially displaceable end support 16 for the work, and so arranged that the action of rotating the sleeve 17 to move the part 16 up against the end of the work causes said arm 27 to pass over the hinged half 12 of the die and automatically fix same in the closed position.

During the shaping operation it is advisable to fix the container or article between end supports, at least one of which exerts a resilient or yielding pressure upon the work. One advantage gained by this is that any elongation or axial contraction of the work which may take place during shaping is allowed for, while another advantage is that the possibility of the work becoming damaged when clamping same in position is minimised.

Let it be assumed that a tubular container is being shaped having its one end closed by a disc or wall portion 13a. The open end or mouth of the container formed with a curled, or partly curled edge, is assembled over or around a spigot or short annular flange 26 projecting from a portion of the head-stock constituting the end support 15 (Figure 8), or in another alternative the open end may be assembled within an annular groove or channel or between inner and

outer annular spigots. The opposite or closed end 13a of the container may be gripped or supported by a resilient or cushion member and/or a resiliently mounted plate, disc or ring. An internal support, such as the flange 26, at the open end of the container is advisable, as same greatly assists in preventing inward collapse of a seam in the container wall.

A rubber or like compressible pad or disc 28 may be fixed to the face of the end support 16, adapted when said end support is moved towards the work to engage the end wall 13a of the container 13 and provide a cushion bearing therefor. Alternatively or additionally, the end support 16 may comprise a plate or the like capable of a limited degree of axial movement relatively to the aforesaid sleeve 17 or other carrier against the resistance of a plurality of small compression springs 29. These springs may be pocketed in the member 16 and in a plate or flange 30 on the sleeve 17, and headed pins or screws 31 co-operating with holes in the flange 30 function to guide and limit the movement of the member 16 against the resistance of the springs 29 (Figure 8). Thus the member 16 is pressed resiliently towards the end of the container being shaped. When dealing with a seamed sheet metal container, the possibility of the seam being broken or burst is also minimised by the use of a compressible pad 28 and/or a spring-mounted end support 16. Instead of, or in addition to, providing the spring-mounted or like resilient support at the closed end of the container, same may be provided at the open end.

The tool 32, operating within the work to shape same to the internal contour of the aforesaid hinged outer die, may embody a plurality of pivoted arms 33 terminating in pressure rollers 34, there being provided means, such for example as those described in the aforesaid patent specification, for variably determining the outward displacement of the pressure members while relative reciprocation is imparted between the tool and the work.

Where the head-stock with the assembled work is reciprocated, means may be provided for automatically rotating the aforementioned rotatable sleeve 17 carrying the resilient or compressible end support so as to press the latter into engagement with the end of the work and subsequently remove same therefrom. This may be accomplished by providing on the sleeve 17 a laterally projecting pin preferably with a roller, which is adapted to coact with an inclined slot or cam groove on a relatively fixed member so that when the head-stock is traversed in one direction the sleeve is rotated and caused to approach the work, and when reciprocated in the opposite direction to recede from the work. The inclined slot or cam groove terminates in a horizontal portion so that when the sleeve has been rotated to the required extent the head-stock can be further traversed without affecting said sleeve.

Where a seamed container is being shaped it is, as aforesaid, advantageous to fix an end wall or base on the container prior to shaping. This serves to lock the seam at one end of the container; and in order to eliminate the possibility of the seam bursting or collapsing at or towards the open end of the container, said seam may be provided at one or more positions in its length with locking means. One method of doing this is illustrated in Figures 5 to 7. The major part of the length of the seam 35 is formed in the usual manner of two oppositely folded edge por-

tions hooked one within the other and cramped together as at 36 in Figure 7. At the open end of the container one edge portion 31 of the seam is entered into the outer fold of a double or S fold 38 formed at the opposed edge portion, thereby positively resisting tendency of the joint collapsing, i. e. displacement of the seamed edges to a greater degree of overlap. If the container is being shaped having in its wall a seam of the customary formation, it is advisable to employ means, such as an internal spigot 26 (Figure 8) for internally supporting the open end of the container. The provision of a locked seam such as above described, however, eliminates or reduces the necessity of employing an internal support for the open end of the container.

It is to be understood, however, that the machine in accordance with this invention can be utilised for shaping either seamed or seamless articles. For example, same can be used for shaping a container of solid drawn metal having an end wall or base integral with the circumferential wall.

I claim:

1. In an apparatus for shaping thin metal tubes or containers of the kind wherein a rotatable expanding tool is introduced axially within the work to operate on the walls thereof to cause them to assume the conformation of a die, work supporting means comprising a pair of supporting members disposed to engage the end portions

5 of the work to support the same, one of said members being provided with an axial hole for the entry of the expanding tool and at least one of said members being axially movable; means 10 for moving said movable member into and out of engagement with the work; a die disposed between said supporting members arranged to circumferentially surround the work, which die is longitudinally divided into a plurality of elements, at least one of which is movable transversely of the axis of the work whereby the latter may be laterally introduced into and withdrawn from the die, and which die is also divided transversely with one portion thereof mounted for limited axial movement relative to the other; and means for retaining said die elements in operative work surrounding position.

2. An apparatus, as set forth in claim 1, having resilient means tending to axially separate the transversely divided parts of the die, and means for limiting the extent of such separation.

3. An apparatus as set forth in claim 1, having resilient means provided at the transverse division of the die tending to axially separate the transversely divided parts thereof, and having said movable work-supporting member arranged to close said die parts against the action of said resilient means as said member moves to work engaging position.

JOHN ARTHUR DOVE.
